UNITED STATES PATENT OFFICE

164,351

HELICOPTER

Francis Peterson Bassett, Lockport, N. Y., assignor to Bell Aircraft Corporation, Wheatfield, N. Y.

Application November 17, 1949, Serial No. 6,084

Term of patent 14 years

(Cl. D71—1)

To all whom it may concern:

Be it known that I, Francis Petersen Bassett, a citizen of the United States, residing at Lockport, New York, in the county of Niagara and State of New York, have invented a new, original, and ornamental Design for a Helicopter, of which the following is a specification, reference being had to the accompanying drawings, forming a part thereof, and wherein certain portions of the dotted line showings have been omitted for convenience in illustration.

Fig. 1 is a side elevational view of a helicopter, showing my design;

Fig. 2 is a top plan view thereof; and

Fig. 3 is a front elevational view thereof.

The characteristic features of my design reside in the portions shown by means of full lines in the drawings.

I claim:

The ornamental design for a helicopter, as shown and described.

FRANCIS PETERSON BASSETT.
